UNITED STATES PATENT OFFICE.

ARTHUR E. COOPER, OF BEACON, NEW YORK.

BILLIARD-CUE HOLDER.

1,393,265.

Specification of Letters Patent. Patented Oct. 11, 1921.

Application filed March 22, 1921. Serial No. 454,599.

To all whom it may concern:

Be it known that I, ARTHUR E. COOPER, a citizen of the United States, residing at Beacon, in the county of Dutchess and State 5 of New York, have invented certain new and useful Improvements in Billiard-Cue Holders; and I do hereby declare the following to be a full, clear, and exact description of the invention, such as will enable others 10 skilled in the art to which it appertains to make and use the same.

The present invention relates to a device for holding or suspending a billiard cue or other similar object or stick and aims to provide a novel and improved as well as simple and inexpensive device of that character into which the cue can be conveniently inserted to be held thereby, and from which the cue can be readily removed.

20 A further object is the provision of such a holder having novel means for receiving and clamping the cue or stick using a gravity roller.

With the foregoing and other objects in view, which will be apparent as the description proceeds, the invention resides in the construction and arrangement of parts hereinafter described and claimed, it being understood that changes can be made within 30 the scope of what is claimed, without departing from the spirit of the invention.

The invention is illustrated in the accompanying drawing, wherein:—

Figure 1 is a front view of the improved 35 holder showing the cue therein.

Fig. 2 is a horizontal section on the line 2—2 of Fig. 1.

Fig. 3 is a vertical section on the line 3—3 of Fig. 1.

40 The holder comprises a vertical back plate 5 of any suitable kind, which, as shown, has its vertical edge portions overlapping and secured to a pair of vertical supporting bars or brackets 6, which have their terminals 45 projecting above the upper and lower edges of said plate for attachment to a wall or other support by means of screws or the like.

A pair of vertical bars 7 and 8 are secured to the plate 5 on the front side thereof, and flange plates or pieces 9 and 10 are secured to the bars 7 and 8, respectively, to form flanges extending toward one another and spaced from the plate 5 and from one 55 another to receive the cue C, and permit of

the convenient withdrawal of said cue from between the bars 7 and 8. Guide pieces 11 and 12 are secured to the front side of the plate 5 at the lower ends of the bars 7 and 8, respectively, or may be portions of said bars, and the guide pieces 11 and 12 have the downwardly diverging surfaces 13 for guiding the tip of the cue between the bars 7 and 8, when the cue is inserted by an upward movement into the holder.

60 The clamping or gripping means includes a channel member 14 of sheet metal or other suitable material secured against the bar 8 between the flange 10 and plate 5, and having a pair of vertically spaced transverse 70 rollers 15 mounted for rotation therein or axles or pins 16 secured to the flanges of said member 14, for the contact of the cue with said rollers.

65 A gravity roller 17 of larger diameter 75 and of rubber or other resilient material is disposed in the groove between the flange 9 and plate 5 opposite to the rollers 15, and the adjacent surface of the bar 7 is inclined, as at 18, whereby the roller 17 in rolling 80 down said inclined surface 18 will roll toward the lower roller 15. The roller 17 can be prevented from being moved upwardly out of its groove, by means of a stop piece 19 secured between the upper end of the 85 flange 9 and plate 5.

75 In using the holder, when the cue is inserted upwardly into the holder, the roller 17 is shoved upwardly, and will gravitate 90 down the inclined surface 18 and lodge between said surface and the cue. The roller 17 will thus bind between the surface 18 and the cue, and will contact with the cue at a point intermediate the points of the cue which contact with the rollers 15, whereby 95 the cue is clamped or gripped between the opposite rollers 15 and 17. The roller 17 is also compressed slightly, whereby to assist in the binding of the cue, and thereby prevent the cue from falling. However, by lifting the cue, the roller 17 is raised, thereby 100 releasing the cue, and permitting it to be lifted forwardly out through the slot. The rollers 15 provide for the free vertical movement of the cue without a scraping or 105 frictional engagement, and thus preserve the cue. The cue is readily inserted by simply raising it into the holder, and then by raising the cue and moving it forwardly, it is readily removed.

Having thus described the invention, what is claimed as new is:—

1. A holder of the kind described having rollers supported in vertically spaced positions for the engagement of a cue or stick, and a gravity member opposite to said rollers for binding against said cue or stick and clamping it against said rollers.
2. A holder of the kind described comprising rollers supported in vertically spaced positions for the engagement of a cue or stick, a member opposite to said rollers having an inclined surface, and a gravity roller rolling on said surface to bind between said surface and cue.
3. A holder of the kind described com-

prising spaced members having a slot between them for the passage of a cue or stick, and providing channels, vertically spaced rollers mounted for rotation in one channel for the contact of a cue or stick, the opposite member having an inclined surface, and a gravity roller movable in the other channel along said surface to gravitate and bind between said surface and cue. 25

In testimony whereof I have signed my name to this specification in the presence of two subscribing witnesses.

ARTHUR E. COOPER.
